UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

LASTING AND THREAD-FASTENING MACHINE.

Application filed September 11, 1919. Serial No. 323,199.

To all whom it may concern:

Be it known that I, FRED N. LA CHAPELLE, a citizen of the United States, residing at Beverly, in the county of Essex and State 5 of Massachusetts, have invented certain Improvements in Lasting and Thread-Fastening Machines, of which the following description, in connection with the accompanying drawings, is a specification, like referring 10 to characters on the drawings indicating like parts in the several figures.

This invention relates to machine for securing in lasted position, the uppers of boots and shoes, and particularly to machines for progressively lasting the uppers 15 and securing them permanently to their innersoles by thread.

The embodiment of the invention selected for illustration is especially adapted for 20 lasting and securing the sides of shoes, the toes of which have preferably been lasted and bound with a wire. It is to be understood, however, that the invention is not limited to such use but may be employed 25 at any time in the manufacture of the shoe and at any part of the shoe where it will perform a useful operation.

It has been proposed to employ thread 30 fasteners to secure the previously lasted upper in lasted position so that the lasting tacks can be removed preparatory to the welting operation. The use of metallic fastenings for holding the upper in lasted position during the welting operation is thus 35 avoided and hence all danger and trouble occasioned by the needle's striking such metallic fastenings are entirely obviated. A machine designed for this work is disclosed and claimed in Letters Patent of the 40 United States No. 1,185,108 granted May 30, 1916, on my application.

An object of this invention is to provide 45 a machine by which the loss of time occasioned by performing the lasting as a separate operation and the expense incurred by the use of temporary lasting fastenings in addition to the fastenings required during 50 welting and subsequent operations as well as other disadvantages above indicated can be avoided, while retaining the advantages characteristically obtained by use of the

machines and thread fasteners of the type set forth in said Letters Patent.

The term "thread fastener" as used herein is intended to mean an individual securing means, formed of thread, which is self-sufficient to hold together fixedly the parts through which the fasteners pass whether the fasteners are connected by thread or not. Conveniently the thread fastener employed may, as shown in said Letters Patent, comprise a pair of loops passing through the work in spaced relation, the first loop being passed inside the second loop and the thread drawn tight, the fastener being in 60 this sense a loop-locked stitch.

Features of the invention consist in an organization including lasting means and means for inserting individual thread fasteners to hold the upper in lasted position. 70

A further feature of the invention consists in a novel organization including lasting means, securing means comprising means for forming individual thread fasteners to secure the upper, and means for feeding the work. Preferably the lasting means consists in means for updrawing and overdrawing a portion of the upper, and the securing means forms through the upper and innersole rib individual thread 80 connected loop locked fasteners or stitches. As shown the loops lie on the inside of the rib or in the channel and the connecting thread lies on the stock covering the feather of the innersole. In the construction shown the lasting means comprises a gripper having jaws which are closed upon the upper, are moved upwardly to tension the upper, and are then moved inwardly of the shoe to lay the upper in proper relation to the 85 innersole rib to be secured by the thread fasteners.

The thread fastener forming mechanism comprises means for passing two loops successively through the upper and innersole rib and for interlocking the loops 95 and drawing on the thread to lock the fastener. The feeding means feeds the work a distance in excess of the length of the fastener so that successive fasteners are 100 separate and distinct, being connected only by a strand of thread which lies on the side of the work next to the machine where it

assists in holding the lasted upper between fasteners. As illustrated, the feeding of the work is effected by movement of the needle and this movement is such that the distance 5 between the fasteners is equal to the length of a fastener. Obviously, however, the distance between the fasteners may be made greater or less than the length of a fastener.

- 10 Another feature of the invention consists in an organization comprising means to cause the needle to pass through the work and withdraw, leaving a loop on the inside of the work, then to cause it to move a 15 fastener length in a direction opposite to the feed of the work and re-enter the work to form a second loop, means for engaging the first loop with the second loop, and means to cause the needle while it is in the 20 work to move in the direction of the feed of the work a distance in excess of the length of the fastener, to withdraw from the work while the stitch is tightened and then to return to initial position.

25 In the drawings:—

Fig. 1 is a side elevation of a machine embodying the invention;

Fig. 2 is an enlarged view in elevation of parts shown in Fig. 1;

30 Fig. 3 is a front elevation of the machine partly in section;

Fig. 4 is a sectional detail illustrating an operation of the machine;

35 Fig. 5 is a perspective view partly in section illustrating the formation of the thread fasteners;

Fig. 6 is a view of the bottom of a shoe having its sides lasted by the machine;

40 Fig. 7 is a cam chart showing the relation of certain cams which operate instrumentalities with which the machine is provided;

Fig. 8 is a view of the toe of a shoe showing the thread carried around the toe to enable the binding wire to be removed.

Referring to Fig. 1 of the drawings, the numeral 2 indicates the column of the machine in which a head frame 4 is supported. A work rest and channel guide 6 is rigidly 50 supported upon a bracket 8 fixed to the frame 4. Journaled in the frame 4 is the main shaft 10 to which are secured the several cam blocks 12, 14, 16 from which operative movements of the lasting and fastener forming instrumentalities are derived. The lasting means comprises a gripper 18 having jaws 20, 22 arranged to receive the upstanding margin of a shoe presented with its innersole rib or channel against the end 55 of the rest 6. The lower jaw 20 is rigidly secured to a gripper shank or casing 24 through which extends a stem 26 connected to the movable jaw 22, the construction being such that depression of the stem 26 will 60 cause the jaw 22 to move toward the jaw 20

to seize the upper. The stem 26 is depressed by a closing lever 28 pivoted on a shaft 30 and having on its rear arm 31 a roll 33 which engages a suitable cam path 35 (Fig. 1) formed in the right hand face 70 of the cam block 12 (Fig. 3.) The closing is effected yieldingly through a spring plunger 32 mounted in a sleeve 34 formed in the outer end of the closing lever 28. The gripper casing 24 is pivoted at 40 to an updraw lever 42 pivoted on the shaft 30 and having on its operating arm a roll 43 engaging a cam path 44 formed in the left hand face of the cam block 16, the path being designed to cause the gripper to move upwardly after 75 closing to tension the upper by an updraw pull. After the updraw the gripper is moved inwardly of the shoe to position the upper as shown in Fig. 4 preparatory to its being secured to the innersole rib. This 80 overdraw movement of the gripper is effected by a lever 46 (Fig. 1) pivoted at 48 and having at its upper end a roll 49 actuated by an open cam formed in the right hand face of the cam block 14. The lever 46 85 is connected to the gripper casing 24 by a link 50 and its motion causes the gripper immediately after the updraw to move inwardly to place the upper in position to be secured. The overdraw movement is rendered yielding by a spring 52 which is tensioned by the cam and allowed to react to effect the overdraw motion of the gripper.

The fastener forming mechanism is in 90 most respects similar to that disclosed and claimed in my prior Letters Patent referred to above. The mechanism comprises a curved eye needle 60 which is actuated to pass successive loops of thread through the material. After the first loop *a* of thread 100 has been passed through the work it is engaged upon the opposite side of the work by a hooked thread finger 62 which holds the loop during the retracting movement of the needle and which is actuated to pass the first loop of thread *a* through the second loop *b* at the proper time. After the formation of the first loop the needle is retracted and given a movement laterally with 105 respect to the needle and opposite to the direction in which the work is to be fed a distance corresponding to the length of a fastener and then re-enters the work to form the second loop *b*. Before the needle is retracted after the formation of the second loop it is given a lateral movement in the direction of the feed of the work equal to the length of a fastener plus the space to be made between fasteners. After the first 110 loop *a* has been passed through the second loop *b* the needle is retracted and a pull is exerted upon the supply end of the thread to draw the loop *a* into the work and lock the stitch. The needle now moves laterally in a direction opposite to the feed of the work 115 120 125 130

a distance equal to the space between fasteners to its initial position ready to form the first loop of the next fastener. In order to clamp the end of the thread in starting 5 and prevent its being drawn through the work the under side of the needle is provided with a groove 64 (Fig. 4) in which the supply side of the loop lies and is allowed to slide freely. When the needle advances the 10 short end of the thread is clamped between the needle and the work and all the thread for the formation of the loop is drawn from the supply side, the advancing movement of the needle being accurately gaged to position 15 the upper side of the loop above the end of the thread finger.

The needle 60 is clamped in the usual manner to a needle segment 66 fulcrumed at 68 and oscillated to impart the proper movements to the needle by a bell crank lever 70, 20 71 fulcrumed on the shaft 30, the arm 70 of the bell crank has a laterally projecting stud 74 upon which a lever 76 is fulcrumed. The lever 76 is connected at its lower end to the 25 upper portion of the needle segment 66 by a link 80. The opposite end of the lever 76 is provided with a bore 82 and a bearing 84 in which is slidably held a pin 86 which is secured to a T-shaped member 88 having 30 a stem journaled in a bearing 90 in a head 91. With this construction, when the bell crank lever 70, 71 is rocked in one direction, for instance clockwise, a rocking movement 35 in the opposite direction or counter-clockwise is imparted to the needle segment through the lever 76 and its link 80. The proper movements are imparted automatically to the bell crank lever 70, 71 by a cam path 92 formed in the left hand face of 40 the cam block 12, the arm 71 of the lever carrying a roll 94 which engages the said cam path. In addition to passing two loops of thread successively through the work a lateral or feeding movement is imparted to 45 the needle between the advancing movements to cause the path of the advancing movement of the needle to be shifted and the needle is also moved laterally after the second advancing movement a greater distance in the 50 opposite direction to effect feeding of the work between the fastener forming operations. As shown herein, in order to impart these lateral feeding movements the needle segment is supported upon the head 91 which 55 is slidably mounted upon parallel guide bars 101, 102 rigidly secured to the machine frame. The proper feed movements are automatically imparted to the head 91 by a path 103 formed in the edge of the cam 60 block 14 which is engaged by a cam roll 104 mounted upon a stud extending upwardly and rearwardly from the head 91 (Fig. 2). In order to maintain the connections 65 for operating the needle segment intact when a feeding movement is imparted to the

needle, the T-shaped member 88 is journaled in a bearing 108 on the head 91 and the bell crank needle lever has upon its arm 70 the laterally extending stud 74 which slidably engages a bearing in the lever 76. The 70 lever 76, therefore, is permitted to slide freely upon the stud which has a sufficient length to allow the necessary lateral or feeding movements of the needle segment to be communicated to it by the cam path 103 and 75 roll 104.

The thread finger 62 which co-operates with the needle 58 in forming the stitch engages the first loop of thread formed by the first passage of the needle through the work 80 and holds it during the retraction of the needle and the formation of the second loop by the needle as it passes through the work a second time in spaced relation from the point of first passage. The thread finger 85 is then actuated to pass the first loop through the second loop and to hold both loops during the retracting movement of the needle so that when the needle is retracted a second time the second loop binds upon the first 90 loop and prevents withdrawal of the second loop with the needle. The finger 62 is supported upon a finger carrying slide 112 which is slidably mounted upon the parallel guides 101, 102 and is actuated to impart 95 linear movements to the finger by a peripheral cam path 114 formed in the cam block 12. The cam path 114 is engaged by a cam roll 116 mounted upon a rearwardly and upwardly projecting stud (Fig. 2) on 100 the finger carrying slide 112. As the thread finger moves in a linear direction it is desirable to raise the upper side of the loop 105 in order that the thread finger shall pass between the side of the loop and the shank of the needle. This is conveniently accomplished by increasing the forward throw of the needle when passing the second loop through the work, and to this end the needle cam is designed to impart two forward throws of 110 varying degree, the second throw being longer than the first as is clearly indicated on the cam chart of Fig. 7.

After both loops of thread have been passed through the work and the first loop 115 of thread has been passed through the second, the needle is given a movement in the direction of feed of the work greater than the length of the stitch in order to provide a space between stitches. The needle then withdraws and a pull is exerted upon the supply end of the thread to draw both loops into the work and lock the stitch. To enable the stitch to be tightened the 120 thread, before passing through the eye of the needle, is carried over a roll 126 journaled in the free end of a take-up lever 128. The take-up lever is fulcrumed at its rear end upon a shaft 130 and is actuated 125 by a cam 131 on the left hand portion of 130

the periphery of the cam block 14 engaged by a roll 132 mounted upon the lever 128 between its ends.

During the operation of the take-up lever 5 the end of the supply thread is locked to prevent more thread being drawn from the supply by a thread clamp 134 which binds the thread to the grooved periphery of a roll 136 supported by a stationary pivot on the frame. The thread clamp 134 is formed upon one arm of a bell crank lever 138, 139 pivotally supported upon the machine frame at 140 and having a roll 142 journaled upon its opposite arm and engaging with an edge 10 cam upon the periphery of the cam block 14. The roll 142 is maintained in engagement with the periphery of the cam by a tension spring 146 connected to the arm 139 of the bell crank. In order to vary 15 the clamping effect of the thread clamp 134 it is provided with an adjusting screw 148 which bears upon a stationary part and limits movement of the thread clamp in the direction to clamp the thread on the roll. In 20 order completely to fill the holes in the work and lock the fastener tightly a waxed thread is conveniently employed, and to this end the thread is led from any convenient type 25 of wax pot 152 over a guide roll 154 to the thread clamp 134.

It is desirable to put some tension on the thread in passing about the toe in order that the upper shall be held tightly by the thread and for this purpose the thread clamp is 30 conveniently utilized as a tension device. The peripheral cam 131 is provided with a recess 158, which allows the thread clamp, under the action of the spring 146, to lock the thread during the action of the take-up 35 and to put tension upon the thread in passing about the toe while the machine is stopped. The locking movement of the thread clamp is determined in each case by the position of the adjusting screw 148 and this movement is sufficient to act as a thread 40 clamp to set the stitch in the work when the take-up acts and put a suitable tension on the thread in passing about the toe.

The machine is provided with the usual 45 needle guide 160 (Fig. 2) which is mounted upon the pivot 68 with the needle segment 66 and carries a toothed segment 162 the teeth of which are in mesh with teeth of the end of a rocking lever 164 (Fig. 3) fulcrumed 50 on the bar 101 and having a rear arm 166 carrying a roll 168 which engages a suitable cam path in the right hand face of the cam block 16.

The machine is driven from a pulley 170 55 on the shaft 10, there being provided between the pulley and the shaft a clutch and brake mechanism of any known type which can be set by a pull on the clutch rod 172 and released by a spring 174. Preferably the clutch is arranged to stop the machine at

the end of the cycle with the gripper open and the needle out of the work provided the rod 172 is released during the cycle.

The mode of operation of the machine is as follows: The side lasting may be done 70 either before or after the end lasting. It is preferable, however, to have the ends of the shoe lasted before it is presented to the machine of the present invention for side lasting. A shoe in this condition is first manipulated by the operator to position the channel guide 6 against the inside of the lip of the innersole or in the channel at a point, for instance the point A (Fig. 6), where the lasting operation is to be begun. The machine is then started by depressing a treadle connected to the rod 172 and the open gripper 18 descends to embrace the upwardly projecting margin of the upper. The gripper is then closed to seize the upper and moved upwardly and over the shoe to dispose the portion of stock being treated in lasted position substantially as shown in Fig. 4. The needle 60 then advances to pass the loop of thread *a* through the upper and lip of the innersole from the outer side of the shoe and the loop is engaged and held during the retracting movement of the needle by the hook shaped end of the thread finger 62. The needle is then withdrawn from the work and the needle carrying slide or head 91 is actuated by the cam path 92 to impart a lateral movement to the needle in a direction opposite to the direction of feed of the work and to locate it in position for the next advancing movement, this feeding movement being the length of the thread fastener to be formed. The needle then advances to pass a second loop *b* of thread through the work, this second advancing movement being 100 greater than the first to allow the thread finger to carry the first loop between the upper strand of the second loop and the shank of the needle. After the thread finger has passed the first loop through the second, the needle, before its retraction, is given a lateral movement in the direction of the feed of the work a distance greater than the length of the fastener to be formed by the space which it is desired to have between 110 fasteners. As shown herein the space between fasteners is equal to the length of a fastener. The needle is then retracted until completely withdrawn from the work, and during this movement the take-up is actuated to pull the second loop into the work and lock the stitch. The needle is then given a lateral movement in a direction opposite to the feed of the work a distance equal to the 115 space provided between the fasteners and is again in initial position ready to begin the formation of a second fastener in spaced relation from the first. The thread is not cut between fasteners but lies along the upper covered feather of the innersole showing as 120 125 130 135

a substantially continuous single thread on that side of the work and holds the lasted upper closely to the rib at all points. On the inner side of the work there is a space 5 between fasteners where there is no thread, as is clearly shown in Fig. 5. The operations described are repeated to last and secure successive portions of the upper progressively along the side of the shoe until the point B 10 is reached. Here the machine may be stopped and the thread cut, the lasting operation being again begun on the opposite side of the shoe at the point C and continued along the side to the point B. If desired, when the point B is reached the thread need 15 not be cut but may be drawn under tension around the toe of the shoe until the point C is reached, as shown in Fig. 8, the lasting and securing being re-commenced at the point C and continued to the point D without cutting the thread. This carrying of the thread about the toe holds the upper in lasted 20 position so that the binding wire and its anchor tacks may be removed, there being 25 then no metallic fastenings in the shoe to interfere with the welting operation.

Having fully described my invention, what I claim as new and desire to secure by Letters Patent of the United States is:

30 1. In a machine of the class described the combination of means for lasting successive portions of a shoe upper and means for securing each portion while held in lasted position by an individual thread fastening 35 which is self-sufficient to hold the upper in fixed position.

2. In a machine of the class described the combination of lasting means, securing means comprising thread fastener forming 40 mechanism, and means to feed the work between fasteners to space the fasteners from each other.

3. In a machine of the class described, the combination of lasting means, means for forming a stitch through the upper and innersole while the work is at rest, and means for feeding the work a distance greater 45 than the length of the stitch after the upper is released by the lasting means.

50 4. In a machine for lasting and securing a shoe upper in lasted position to an innersole, the combination of a gripper for progressively working successive portions of an upper over the last, a channel guide, and 55 thread fastener forming and inserting devices co-operating during each cycle of operations of the machine to form and insert a thread fastener through the upper and innersole rib of the shoe.

60 5. In a machine for lasting and securing a shoe upper in lasted position to an innersole, the combination of a gripper for progressively working successive portions of an upper over a last, a channel guide, thread 65 fastener forming and inserting devices co-

operating during each cycle of operations of the machine to form and insert a thread fastener through the upper and innersole rib of the shoe, and means for advancing the shoe to cause the thread fasteners to be 70 spaced apart.

6. In a machine of the class described, the combination of lasting means, and means for inserting individual thread fasteners to hold the lasted upper in position. 75

7. In a machine of the class described, the combination of lasting means for progressively working successive portions of an upper over a last, and thread fastener mechanism acting to form through the lasted 80 upper and innersole rib an individual thread fastener for each operation of the lasting means.

8. In a machine of the class described, the combination of means for lasting successive 85 portions of a shoe upper, with thread fastener forming and inserting devices operating in each cycle of operations of the lasting means to form and insert a thread fastener through the upper and innersole rib 90 of the shoe to hold the lasted upper in position.

9. In a machine of the class described, the combination of a gripper for progressively 95 working successive portions of an upper over a last, work positioning means, and mechanism for passing two loops of thread successively through the lasted upper and innersole rib on the outer side of the shoe, for passing the first loop of thread through 100 the second upon the inner side of the rib, for releasing the encircled loop, and for pulling upon the supply thread from the first side to draw the second loop into the work and lock the stitch. 105

10. In a lasting machine, the combination of a gripper, means for operating the gripper to work successive portions of the upper into lasted position, and means for inserting individual non-metallic fastenings to secure the upper in lasted position. 110

11. In a lasting machine, the combination of a gripper, means for operating the gripper to work successive portions of the upper into lasted position, and thread 115 fastening mechanism constructed and arranged to insert through the upper and innersole rib individual fastenings of thread as the lasting progresses.

12. In a lasting machine, the combination of a gripper, means for operating the gripper to work successive portions of the upper into lasted position, and thread fastening mechanism constructed and arranged to insert through the upper and innersole rib individual fastenings of thread comprising two loops passed through the upper and innersole and interlocked on the inner side of the rib. 125

13. In a lasting machine, the combina- 130

- tion of a gripper, means for operating the gripper to work successive portions of the upper into lasted position, and thread fastener forming means operating in timed relation to the gripper to fasten successive spaced portions of the upper in lasted position and to feed the work between fastenings.
14. In a lasting machine, the combination of a gripper, means for operating the gripper to work successive portions of the upper into lasted position, and thread fastening means operating in timed relation to the gripper to fasten successive portions of the upper in lasted position by passing pairs of loops through the upper and rib and interlocking the loops.
15. In a machine of the class described, a lasting gripper arranged for continuous operation to tension successive portions of a shoe upper into lasted position, combined with thread fastening-mechanism comprising an eye pointed needle, means to operate the needle to pass successive loops of thread through the upper and innersole rib, and means to engage one loop and pass it through the next loop to form the fastening.
16. In a machine of the class described, the combination of means for progressively lasting an upper over a shoe bottom means for forming individual, loop-locked, thread fasteners through the lasted upper and innersole rib, the thread being carried from fastener to fastener on the outside of the upper overlying the rib and acting to hold the upper in position between fasteners.
17. In a machine of the class described, the combination of a lasting means, securing means comprising thread fastener forming mechanism including a needle, and means for moving the needle to feed the work between fasteners while the fastener forming mechanism is idle to space the fasteners from each other.
18. In a machine of the class described, the combination of lasting means, means including a needle for forming a stitch through the upper and innersole while the work is at rest, and means for operating the needle to feed the work a distance greater than the length of the stitch after the upper is released by the lasting means.
19. In a machine for lasting and securing a shoe upper in lasted position to an innersole, the combination of a gripper for progressively working successive portions of an upper over the last, a channel guide, and thread fastener forming and inserting devices including an eye-pointed needle co-operating during each cycle of operations of the machine to form and insert a thread fastener through the upper and innersole rib of the shoe.
20. In a machine for lasting and securing a shoe upper in lasted position to an innersole, the combination of a gripper for progressively working successive portions of an upper over a last, a channel guide, thread fastener forming and inserting devices including a needle co-operating during each cycle of operations of the machine to form and insert a thread fastener through the upper and innersole rib of the shoe, and means for operating the needle to advance the shoe to cause the thread fasteners to be spaced apart.
21. In a machine for lasting and securing shoe uppers in lasted position to the innersoles, the combination of a gripper for progressively working successive portions of an upper over a last, a channel guide, thread fastener forming and inserting devices comprising a needle and means for causing the needle while in initial position to pass through the lasted portion of the upper and the innersole rib and then withdraw leaving a loop in the work, means for moving the needle in one direction the length of a fastener and for causing the needle again to enter the work, means for causing the first loop to engage and lock the second loop, and means for causing the needle while in the work to move in the opposite direction a distance greater than the length of the fastener and for returning the needle after retraction to its initial position.
22. In a machine of the class described, the combination of a gripper for updrawing and overdrawing the upper, a needle, mechanism for causing the needle to pass through the work and form a loop, withdraw and move a fastener length in a direction opposite to the feed of the work and re-enter the work to form a second loop, means for engaging the first loop with the second loop, and means for causing the needle to move in the direction of feed of the work the length of two fasteners and to repeat its operations.
23. In a machine for lasting and securing shoe uppers in lasted position to the innersoles, the combination of a channel guide, thread fastener forming and inserting devices comprising a needle and means for causing the needle while in initial position to pass through the lasted portion of the upper and the innersole rib and then withdraw leaving a loop in the work, means for moving the needle in one direction the length of a fastener and for causing the needle again to enter the work, means for causing the first loop to engage and lock the second loop, and means for moving the needle while in the work in the opposite direction a distance greater than the length of the fastener and for returning the needle after retraction to its initial position.
24. In a machine of the class described, the combination of a needle, mechanism for causing the needle to pass through the work

- and form a loop, withdraw and move a fastener length in a direction opposite to the feed of the work and re-enter the work to form a second loop, means for engaging 5 the first loop with the second loop, and means for causing the needle to move in the direction of feed of the work the length of two fasteners, return to initial position and repeat its operations.
- 10 25. In a machine of the class described, the combination of means for successively lasting portions of a shoe upper, thread fastener forming and inserting mechanism operating in each cycle of operations of the 15 lasting means to form and insert a thread fastener through the upper and innersole rib of the shoe to hold the lasted upper in lasted position, and means for feeding the work at least the length of a fastener between cycles 20 of the lasting and fastener forming and inserting mechanism.
26. In a machine of the class described, the combination of a gripper for progressively working portions of an upper over 25 a last, work positioning means engaging the inner face of the rib of the innersole, and mechanism for passing loops of thread successively through the lasted upper and innersole rib from the outer side of the shoe 30 inwardly, for passing the first loop of thread through the second loop upon the inner side of the rib, for releasing the encircled loop and for pulling upon the supply thread from the outer side to draw the second loop 35 against the first loop to lock the stitch.
27. In a lasting machine, the combination 40 of a gripper, means for operating the gripper progressively to work portions of the upper into lasted position, thread fastener forming mechanism constructed and arranged to insert through the lasted portion of the upper and innersole rib individual fasteners of thread comprising two loops passed through the upper and innersole rib and interlocked 45 on the inner side of the rib, and means for relatively advancing the shoe and the fastener mechanism to cause the lasted and fastened portions to be spaced from each other.
- 50 28. In a lasting machine, the combination 55 of a gripper, means for operating the gripper to tension successive portions of the upper and work them into lasted position, thread fastener forming means operating in time relation to the gripper to fasten the 60 portions of the upper in lasted position by passing loops of thread through the tensioned upper and the rib of the innersole and interlocking the loops, and a work engaging member arranged to oppose the tensioning pull of the gripper and to support the rib during the passage of the loops through it.
- 65 29. In a machine of the class described, the combination of a rest engaging the shoe bottom on the inner side of the innersole 70 rib, a lasting gripper arranged for continuous operation progressively to tension portions of the shoe upper into lasted position in opposition to said rest, and thread fastener forming mechanism comprising an eye-pointed needle, means to operate the needle to pass successive loops of thread through the upper transversely through the innersole rib supported by said rest and means to engage one loop and pass it through the 75 next loop to form a fastener.
30. In a machine of the class described, the combination of means for progressively lasting an upper over a shoe bottom, means for forming individual loop-locked thread 80 fasteners through the lasted upper and innersole rib, and means for causing an element of said fastener forming means to feed the work while the remaining elements are idle to carry the thread from fastener to 85 fastener on the outside of the upper overlying the rib and hold the upper in position between fasteners.
31. In a machine organized for lasting 90 and securing an upper to a sole, the combination of a gripper operated to last a portion of upper in each cycle, and a needle constructed and arranged to penetrate the lasted portion of upper a plurality of times 95 in each cycle of the gripper.
32. In a machine organized for lasting 100 and securing an upper to a sole, the combination of a gripper operated to last a portion of upper in each cycle, and a needle arranged to make two penetrating movements through the tensioned upper in each cycle of the gripper.
33. In a machine organized for lasting 105 and securing an upper to a sole, the combination of a gripper operated to last a portion of upper in each cycle, and a needle constructed and arranged to have a plurality of lateral movements in the same direction in each cycle.
34. A machine of the class described having, in combination, a gripper, means for giving the gripper an updraw and an overdraw movement in each cycle, a needle, means for giving the needle a plurality of upper penetrating movements in each cycle 110 of the gripper, and means for giving the needle a plurality of lateral movements in each cycle.
35. A machine of the class described having, in combination, a gripper, means for giving the gripper an updraw and an overdraw movement in each cycle, a needle, means for giving the needle a plurality of upper penetrating movements in each cycle, and means for moving the needle laterally 115 to space the points of penetration from each other.
36. A machine of the class described having, in combination, a gripper, means for giving the gripper an updraw and an over- 120
- 125
- 130

draw movement in each cycle, a needle, means for giving the needle a plurality of upper penetrating movements in each cycle, and means for moving the needle to space the points of penetration from each other and another movement to feed the work.

37. In a machine organized for lasting and securing an upper to a sole, the combination of a gripper operated to last a portion of upper in each cycle, and a needle constructed and arranged to have two penetrating movements and three lateral movements in each cycle of the gripper.

38. In a machine organized for lasting and securing an upper to a sole, the combination of a gripper operated to last a portion of upper in each cycle, and a needle constructed and arranged to have two penetrating movements and three lateral movements in each cycle of the gripper, one lateral movement occurring while the needle is in the work and being equal to the other two which occur while the needle is out of the work.

39. In a machine organized for lasting and securing an upper to a sole, the combination of a gripper operated to last a portion of upper in each cycle, and a needle constructed and arranged to have more than two lateral movements in each cycle of the gripper, one lateral movement being equal to the others and in the opposite direction.

40. In a machine for lasting and securing an upper to a sole, the combination of a gripper operated to last a portion of upper in each cycle, and a needle operating mechanism constructed and arranged to give the needle two lateral movements in one direction and one lateral movement in the other direction in each cycle.

41. A machine of the class described having, in combination, a gripper, means for giving the gripper an updraw and an overdraw movement in each cycle, a needle, and means for giving the needle a plurality of upper penetrating movements and a plurality of lateral movements in each cycle of the gripper.

42. A machine of the class described having, in combination, a gripper, means for giving the gripper an updraw and an overdraw movement in each cycle to tension an upper, a needle, means for giving the needle a plurality of upper penetrating movements in each cycle of the gripper to carry the loops of thread through the tensioned upper and the innersole rib, means for moving the needle to space the points of penetration from each other, and means to interlock the loops and form a thread fastening self-sufficient to hold the lasted upper in position.

43. A machine of the class described having, in combination, a gripper, means for giving the gripper an updraw and an over-

draw movement in each cycle, a needle, means for giving the needle a plurality of stock penetrating movements in each cycle to carry loops of a single thread through the upper and the rib of the innersole, means for giving the needle a movement to space the points of penetration from each other, means for interlocking the loops, and means for giving the needle another movement while in the work to feed the work.

44. In a shoe sewing machine, the combination of thread fastener forming and inserting mechanism operating in each cycle of the machine to form and insert a thread fastener through the upper and innersole rib of the shoe to hold the upper in lasted position, and means for feeding the work more than the length of a fastener between cycles of the fastener forming and inserting mechanism.

45. In a machine for securing an upper to an innersole, thread fastening forming mechanism constructed and arranged to insert through a portion of the upper and innersole rib individual fastenings of thread comprising two loops passed through the upper and innersole rib and interlocked on the inner side of the rib, the first loop being inside the second loop, and means for relatively advancing the shoe and fastening mechanism to cause the fastened portions to be spaced from each other.

46. In a machine for sewing an upper to an innersole, the combination of means for forming individual loop-locked thread fasteners to secure the upper to the innersole rib, and means for causing an element of said fastener forming means to feed the work while the remaining elements are idle to carry the thread from fastener to fastener on the outside of the upper overlying the rib and hold the upper in position between the fasteners.

47. In a machine organized for securing an upper to a sole by a single thread, the combination of a needle, and needle operating mechanism constructed and arranged to give the needle a plurality of lateral movements in the same direction and a greater lateral movement in an opposite direction in each cycle of the machine and to operate the needle to penetrate the upper and sole.

48. In a machine for securing an upper to a sole having, in combination, a needle, means for giving the needle a plurality of upper penetrating movements in each cycle, and means for moving the needle to space the points of penetration from each other and giving the needle another movement while in the work to feed the work a distance equal to twice the space between the points of penetration.

49. In a machine organized for securing an upper to a sole, the combination of a

needle and means constructed and arranged to give the needle two penetrating movements only and three lateral movements only in each cycle of the machine.

5 50. In a machine organized for securing an upper to a sole, the combination of a needle, operating mechanism therefor constructed and arranged to give the needle two stock penetrating movements and three lateral movements in each cycle of the machine, the operating mechanism therefor effecting said movements in timed relation and causing one lateral movement to occur while the needle is in the work and the other two to occur while the needle is out of the work, the one lateral movement being equal in extent to the sum of the two other lateral movements.

20 51. In a machine organized for securing an upper to a sole, the combination of a needle, and operating mechanism for giving the needle three lateral movements in each cycle of the machine and to cause one

lateral movement to be longer than the other two and to occur between them. 25

52. In a machine of the class described, the combination of a needle, and means for giving the needle a plurality of stock penetrating movements and a greater number of lateral movements one of which is equal to the sum of the others in each cycle of the machine. 30

53. A shoe sewing machine having, in combination, a needle, means for giving the needle a plurality of stock penetrating movements in each cycle to carry loops of a single thread through the upper and the rib of the innersole, means for causing the needle to space the points of penetration from each other, means for placing one loop inside the other, and means for giving the needle another movement while in the work to feed the work. 35

In testimony whereof I have signed my name to this specification.

FRED N. LA CHAPELLE.
